Primary Examiner — Michael C Stout*Assistant Examiner* — Melvin L Davis(74) *Attorney, Agent, or Firm* — Justin Lampel(57) **CLAIM**

The ornamental design for a tank pool float, as shown and described.

DESCRIPTION

FIG. 1 is a perspective view of the tank pool float showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a partial enlarged view of portion 9 in FIG. 1.

The evenly broken line showing of the tank pool float is for the purpose of illustrating portions of the article that forms no part of the claimed design.

The dot-dash boundary lines in FIGS. 1 & 9 demarcate claimed areas that have been enlarged for clarity while the lines themselves do not form part of the claimed design.
